COMBINATION FOUNTAIN PEN AND PENCIL

Filed April 24, 1930

INVENTOR

Solomon M. Sager

By Charles Marshall Atty

UNITED STATES PATENT OFFICE

SOLOMON M. SAGER, OF EVANSTON, ILLINOIS

COMBINATION FOUNTAIN PEN AND PENCIL

Application filed April 24, 1930. Serial No. 446,808.

This invention relates to an improved type of combination visible ink fountain pen and pencil with the fountain pen portion constructed with a transparent barrel 5 adapted to permit viewing of the ink supply within the barrel and embracing a connecting unit between the fountain pen and the pencil units adapted to enclose the eraser carrying head of the plunger mechanism 10 of the fountain pen and the lead magazine end of the pencil unit thereby obviating any necessity of sacrificing any of the space required for the ink supply of the fountain pen unit which has heretofore been necessary in other types of combination writing instruments, due to the fact that the inner end of the pencil unit projects into the interior of the barrel of the fountain pen, thereby using up a portion of the space required for the storage of a supply of ink. 15

It is an object of this invention to provide a combination visible ink fountain pen and a mechanical pencil.

It is also an object of this invention to 25 provide an improved combination visible ink fountain pen and pencil coupled by means of a partitioned connecting sleeve to permit joining of the fountain pen and pencil without reducing the ink capacity of 30 the fountain pen.

It is a further object of this invention to provide a combination fountain pen and pencil wherein the plunger filling mechanism of the fountain pen is provided with

35 an eraser normally adapted to be enclosed by a partitioned coupling removably connecting the pencil with the fountain pen.

It is furthermore an object of this invention to provide a combination visible ink 40 fountain pen of the plunger filling type and a magazine pencil connected by means of a partitioned coupling which conserves the ink carrying space of the fountain pen and furthermore prevents access from being had 45 to the operating mechanism of the fountain pen when the pencil unit is removed from the coupling.

It is an important object of this invention to provide an improved type of combination visible ink type of fountain pen and a

mechanical pencil adapted to be connected by means of a coupling sleeve which is partitioned to provide end chambers for the reception of the inner end of the fountain pen and pencil units to enclose the eraser carrying end of the fountain pen plunger filling mechanism and affording a suitable closure for the open end of the lead carrying magazine of the pencil. 55

Other and further important objects of 60 this invention will be apparent from the disclosures in the specification and the accompanying drawing.

The invention (in a preferred form) is 65 illustrated in the drawing and hereinafter more fully described.

On the drawing:

Figure 1 is an elevational view of an improved combination visible ink fountain pen and pencil with the cap partly broken away 70 and shown in section and engaged on the fountain pen end of the device.

Figure 2 is a perspective view of the improved combination fountain pen and pencil with the cap removed and showing the 75 transparent barrel of the fountain pen with a visible supply of ink.

Figure 3 is an enlarged longitudinal sectional view taken through the pencil supporting end of the device with parts shown 80 in elevation.

Figure 4 is an end view of the inner end of the pencil unit illustrating the location of the lead carrying magazine. 85

As shown on the drawing:

The reference numeral 1 indicates a fountain pen body or barrel constructed of a transparent material and having one end thereof closed by means of a chambered body section or head 2 which is axially passed and has the chamber thereof opening outwardly through the outer end of the closure head 2 to provide a suitable recess for the reception of an improved packing unit 90 consisting of a plurality of adjacently positioned packing discs or rings 3, each of which is constructed of a thin layer of cork having secured to the side surfaces thereof layers of paper or cloth impregnated with 95 a liquid covering of celluloid or pyroxylin. 100

- Positioned adjacent the outermost packing disc or ring 3 is a packing disc or ring 4 constructed of hard rubber or other suitable material. Positioned adjacent the outer side 5 of the hard rubber packing member 4 is a packing ring or disc 5 constructed of soft rubber or other suitable material with the inner diameter of the washer or disc 5 slightly smaller than the inner diameters of 16 the packing members 3 and 4 so that the inner peripheral surface of the packing member 5 will act as a wiping surface as hereinafter more fully described.
- Positioned adjacent the outer surface of 15 the soft rubber packing disc or ring 5 is a packing ring or disc 6 constructed of hard rubber or other suitable material. Threaded into the outer end of the closure head 2 is an externally threaded thimble or bushing 7, 20 the inner end of which is adapted to contact the outermost packing ring 6 and tightly compress the various packing members forming the packing unit in the closure head 2. A portion of the bushing 7 projects outwardly beyond the outer end of the closure head 2.
- Slidably engaged through the closure head 2 and the packing unit therein and projecting into the barrel 1 is a plunger stem 30 8 having adjustably engaged on the outer end thereof a closure cap 9 having a compressible packing sleeve or collar 10 engaged therein and adapted to be brought into contact with the outer end of the plunger stem 35 8 to permit the packing sleeve or collar to be compressed with the adjustment of the closure cap 9 on the stem 8. The outer end of the closure cap 9 is provided with a pocket or recess for the reception of an eraser 11. 40 Secured on the inner end of the plunger stem 8 is a plunger head 12 having a pair of spaced stop flanges between which a plurality of movable and relatively shiftable plunger head packing discs or rings 13 are 45 mounted. The interior surface near one end of the fountain pen barrel 1 is provided with a plurality of longitudinally disposed ink outlet passages or recesses 14 which are separated by reinforcing ribs of the same 50 thickness as the thickness of the walls of the barrel 1 so that the recessed or passaged portion of the fountain pen barrel is strengthened with the ribs separating the 55 passages or recesses 14 serving as guide members or retaining means for the plunger head packing discs 13 so that said packing discs are held in proper position against diametrical expansion into the recesses or 60 passages 14.
- Secured in the passaged end of the fountain pen barrel 1 adjacent the externally threaded portion 15 of said barrel is a fountain pen section 16 provided with a peripheral stop flange or shoulder 17 adjacent the 65 inner end of an ink guard sleeve or collar 18

which is integrally formed on the outer end of the section 16 and provides an inner peripheral chamber for the reception and temporary storage of excess ink returned from the pen point 19 and a feed bar 20. The pen point and the feed bar are engaged through the ink guard 18 and have the inner ends thereof secured in the axial passage provided in the section 16. The inner peripheral surface of the ink guard 18 is out of contact with the pen point and the feed bar, thereby providing a chamber around the pen point and feed bar for the reception of excess or returned ink to prevent the excess ink from settling on the outer end of the ink guard 18 and also obviating the accumulation or settling of ink against the stop flange 17 of the section 16. The excess ink in the ink guard is thus permitted to gradually pass backwardly through the feed passage of the feed bar into the fountain pen barrel 1.

Removably engaged on the pen point end of the fountain pen barrel 1 is a fountain pen cap 21 provided with an internally threaded section 22 in the inner peripheral surface thereof a short distance from the outer or open end of said cap to permit the cap section 22 to have threaded engagement with the threaded section 15 of the fountain pen barrel. Seated or secured in the closed end of the fountain pen cap 21 is a stop sleeve 23 the outer end of which provides a stop shoulder adapted to seat against the stop flange 17 of the section 16 with the ink guard 18 projecting into the stop sleeve 23 as clearly illustrated in Figure 1.

Removably threaded on the outer end of the bushing 7 is one internally threaded end of a union or coupling 24 which is also internally threaded at its opposite end. Secured or integrally formed transversely within the coupling sleeve 24 is a partition 25 dividing the interior of the coupling sleeve into a chamber 26 and a chamber 27. The chamber 26 is provided for enclosing the plunger head 9 and the eraser 11 as illustrated in Figure 3, and when the coupling sleeve 24 is engaged on said bushing 7 the plunger head and the eraser are completely enclosed by means of the partition 25.

Removably engaged in the outer end of the coupling sleeve 24 is an externally threaded neck or collar 28 which is integrally formed on one end of a pencil body section 29 which is provided with a magazine or lead receiving chamber 30 for the storage of extra leads 31 around an axially disposed sleeve or tube 32 in which the lead feeding and retracting mechanism of the pencil are mounted. Connected with the sleeve 32 and rotatable with respect to the pencil housing 29 is a lead feed tip or end section 33, the tapered outer end of which is passaged for 130

the reception of a stick of writing lead 34 which is adapted to be fed outwardly or retracted into the tip 33 when said tip is rotated with respect to the body section 29 of the pencil mechanism. The threaded collar 28 of the pencil mechanism is adapted to be threaded into the interiorly threaded chamber 27 of the coupling sleeve 24, thereby removably holding the fountain pen and the pencil connected together by means of said coupling sleeve 24 as clearly illustrated in Figure 3.

Attention is called to the fact that the partition coupling sleeve 24 is provided with the two separated chambers 26 and 27 permitting the pencil to be coupled with the fountain pen without projecting directly into the fountain pen barrel to reduce the ink capacity of the fountain pen. The double chambered coupling 24 affords a suitable removable closure for the plunger head and the eraser 11 attached thereto in addition to affording a suitable way for connecting the mechanical pencil with the fountain pen without interfering with the ink capacity of the fountain pen.

When it is desired to use the fountain pen the closure cap 21 is removed from the pen point end of the fountain pen barrel and the coupling sleeve 24 is unthreaded from the bushing 7, thereby exposing the plunger head 9. The pen point 19 should now be positioned above a receiving receptacle of any kind or in a bottle or ink and the plunger mechanism should then be pulled outwardly by means of the plunger head 9, thereby causing air or any ink remaining from a previous filling to be ejected outwardly through the inner open end of an ink intake tube 35 one end of which is secured in the inner end of the feed bar 20. The intake tube 35 projects into the fountain pen barrel 1 and into the plunger stem 8 as illustrated in Figure 3, so that when the compressible valve collar or sleeve 10 within the plunger cap 9 is moved outwardly out of engagement with the ink intake tube 35 with the outward movement of the plunger mechanism, the contents of the fountain pen barrel 1 is permitted to be ejected through the tube 35 and the intake passage of the feed bar 20 so that the interior of the fountain pen is thoroughly cleaned out with the outward stroke of the plunger mechanism.

To fill the fountain pen, the pen point and the tip of the feed bar 20 are projected into a supply of ink and the plunger mechanism is pushed inwardly, thereby creating a suction or vacuum action within the fountain pen barrel 1, causing a fresh supply of ink to be pulled upwardly through the feed bar passage and the feed tube 35 into the interior of the plunger stem 8 and out through an opening 36 in the plunger stem 8 to enter

the ink chamber of the fountain pen barrel 1. A supply of ink 37 is thus adapted to be admitted into the transparent barrel of the fountain pen with the downward or inward stroke of the plunger mechanism permitting the supply of ink 37 to be clearly visible through the transparent barrel 1 as clearly illustrated in Figure 2 of the drawing, so that a person may readily observe the amount of ink contained within the fountain pen.

When the fountain pen has been filled as described, the coupling sleeve 24 is again threaded onto the threaded bushing 7, thereby connecting the mechanical pencil with the fountain pen. When the fountain pen is in use and the closure cap 21 is removed from the pencil point end of the device said cap may be removably engaged over the pencil end of the device, if desired. To use the eraser 11, it is only necessary to unscrew the coupling sleeve 24, thereby exposing the eraser 11 which may be conveniently used. To replace the lead in the pencil, it is only necessary to unthread the pencil body section 29 from the outer end of the coupling 24 to permit a used lead to be removed from the magazine chamber 30 for insertion into the outer end of the tip section 33 forming a part of the pencil mechanism.

It will, of course, be understood that various features of construction may be varied through a wide range without departing from the principles of this invention, and it is, therefore, not the purpose to limit the patent granted hereon otherwise than necessitated by the scope of the appended claims.

I claim as my invention:

1. A writing instrument comprising, a fountain pen having an ink visible barrel with a plunger rod reciprocable therein and extending therefrom terminating in a plunger head, a casing provided with means defining a chamber adapted to receive pencil leads and being open at one end to permit removal or insertion of said leads, and a cylindrical member removably connecting said pen and said casing, said member having an interior partition providing closure means for the plunger head and of said pen and for an end of said casing, said casing being insertible in said cylindrical member to abut said partition.

2. In combination, a fountain pen having a barrel with a plunger rod reciprocable therein and extending therefrom terminating in a plunger head, a casing provided with means defining a chamber adapted to receive pencil leads and being open at one end to permit removal or insertion of said leads, means to enclose said plunger head and to provide support for and a closure for said casing, said means comprising a cylindrical coupling member removably connect-

ing said pen and said casing, said member having an interior partition, said casing being insertible in said member to abut said partition.

5 In testimony whereof I have hereunto subscribed my name at Chicago, Cook County, Illinois.

SOLOMON M. SAGER.
